DESIGN FOR A TEXTILE FABRIC

Curt Erwin Forstmann, Montclair, N. J.

Application January 5, 1935, Serial No. 54,742

Term of patent 14 years

To all whom it may concern:

Be it known that I, Curt Erwin Forstmann, a citizen of the United States, residing at Montclair, in the county of Essex and State of New Jersey, have invented a new, original, and ornamental Design for a Textile Fabric, of which the following is a specification, reference being had to the accompanying drawing, forming part thereof.

In the drawing, the sole figure of which is a plan view of a piece of the textile fabric embodying the design of the present invention, the cloth depicted is of a single color.

The design comprises spaced undulating series of parallel bars arranged in stepped relation, and parallel series of spaced bars perpendicular thereto, the bar of the undulating series being more closely woven than the perpendicular bars, and the background between the undulating series having a somewhat puckered appearance.

I claim:

The ornamental design for a textile fabric, as shown and described.

CURT ERWIN FORSTMANN.
